UNITED STATES PATENT OFFICE

MORTON G. BUNNELL, OF PORTER, INDIANA, ASSIGNOR, BY MESNE ASSIGNMENTS, TO
GILLETTE SAFETY RAZOR COMPANY, A CORPORATION OF MASSACHUSETTS.

SAFETY-RAZOR

1,065,109.

Specification of Letters Patent.

Patented June 17, 1913.

Application filed May 11, 1908. Serial No. 316,387.

To all whom it may concern:

Be it known that I, MORTON G. BUNNELL, a citizen of the United States of America, and resident of Porter, Indiana, have invented a certain new and useful Improvement in Safety-Razors, of which the following is a specification.

My invention contemplates a safety razor in which the flexibility of the blade constitutes the expedient for inserting and removing the blade. The nature and advantage of my invention will, however, herein-after more fully appear.

In the accompanying drawings—Figure 1 is a top plan of a razor embodying the principles of my invention; Fig. 2 is a vertical section of the same; Fig. 3 is a rear view of the razor; Fig. 4 is a plan of the blade; and Fig. 5 is an enlarged detail view showing the manner in which the lugs hold the corners of the blade.

In the present illustration my improved safety razor is shown as comprising a flat, rectangular, flexible blade A, having two cutting edges and four corners. The blade is sufficiently flexible that it may be compressed endwise between the thumb and forefinger. The holder-portion B is shown comprising a plate having a flat seat b, for the blade. Four overhanging lugs b', one for each corner of the blade, are shown carried by the plate-portion of the holder. The lugs are shown rigidly carried by the plate and each rigid relative to the others, and so positioned on the respective ends of the holder that the smallest distance between the overlapping portions of the lugs on each side of the holder is less than the length of the blade, and that the smallest distance between the overlapping portions of the lugs on each end of the holder is less than the width of the blade. The disposition of the lugs herein illustrated leaves the upper surface of the blade practically fully exposed and free to be flexed away from the blade-seat in removing and inserting it in position. The lugs illustrated are shown so located that each will engage the blade and diagonally overlap the corner thereof. The lugs will prevent edgewise movement of the blade in all directions, as well as prevent movement away from the blade-seat of the holder. The ends of the holder are shown provided with notches b². The notch b² at each end extends inwardly beyond the inner sides of

the overhanging portions of the lugs b' at that end. This disposition of the notches permits the blade to be compressed endwise between the thumb and forefinger to such an extent that the ends of the blade will assume a position inwardly of the overhanging portions of the lugs at the respective ends and the blade caused to buckle or hump up from its seat and its corners pass inwardly from under the overhanging portions of the lugs and thus be disengaged from the same. Thus the flexibility of the blade constitutes the expedient by which the blade is inserted and removed. The four lugs are all rigidly connected, since they are integral with the top plate of the holder.

As a means of starting the upward bending of the blade, the handle C is provided internally with a plunger c held normally down by a spring c'. The lower end c² of this plunger projects at the lower end of the handle. A slight upward pressure on the plunger is sufficient to start the blade and allow it to flex under the pressure of the thumb and forefinger.

With my improved arrangement no movable clamping or holding parts are necessary for the holder, and in addition the blade is left exposed—that is to say, the smooth upper surface of the blade is left uncovered.

It will be seen that each lug b' engages both longitudinal and transverse edges of the blade.

The holder has the usual guard D.

It will be seen that the overhanging portions of the lugs b' constitute holding means for disengaging the blade when it is flexed to draw its two ends toward each other. It will also be seen that the portions of these lugs which engage the ends or edges of the blade constitute means for preventing displacement of the blade in the plane thereof. The formation of the blade and also of the lugs can, however, be changed or modified without departing from the spirit of my invention, so long as the flexibility of the blade constitutes the expedient for inserting and removing the same—that is, for engaging its ends in and disengaging them from any suitable holding means with which the razor is provided.

It will be seen that the four holding lugs engage oppositely facing edges on the blade, and that the main body of the blade is left free to be flexed when it is inserted and re-

moved, the tendency of the blade to straighten out being utilized to hold it down in place on the holder.

What I claim as my invention is:—

- 5 1. In a safety razor, the combination with a flexible blade, of a holder comprising a blade-seat, a guard, and holding means rigidly mounted on said blade-seat for holding the blade firmly in position when inserted 10 and from which the blade is disengaged by flexing the same and means for flexing said blade.
2. In a safety razor, the combination with a flexible blade, of a holder comprising a 15 blade-seat, a guard, and holding means rigidly mounted on said blade-seat for holding the blade firmly in position when inserted and from which the blade is disengaged by flexing the same, and means for flexing the 20 blade while in the holder for effecting its removal therefrom.
3. A razor comprising a guard, a flexible blade, a holder, and a plurality of securing means rigidly carried by the holder and

provided with portions for overlapping the 25 blade, the overlapping portions on each side being separated one from the other by a distance less than the length of the blade and overlapping the ends of the blade at its corners, whereby it is necessary to flex the blade 30 to engage it with and disengage it from the said securing means, and means for flexing the blade to effect its removal from the holder.

4. In a safety razor, the combination of a 35 flexible blade, a holder provided with means for engaging the ends of the blade, leaving the blade free to be flexed, and a plunger for flexing and lifting the middle of said blade, to draw its two ends toward each other, for 40 the purpose set forth.

Signed by me at Chicago, Ill., this 21st day of April, 1906.

MORTON G. BUNNELL.
